(57) **CLAIM**

The ornamental design for a casing for a hand held communications device holder, as shown and described.

DESCRIPTION

This application is related to U.S. Design Pat. application No. 29/131,452 entitles “Hand Held Communications Device Holder” filed concurrently herewith.

FIG. 1 is a perspective view of a casing for a hand held communications device holder with its lid in an opened position showing the new design;

FIG. 2 is a perspective view of the casing with its lid in a closed position;

FIG. 3 is a top plan view of the casing with its lid in the closed position;

FIG. 4 is a bottom plan view of the casing;

FIG. 5 is a left side elevational view of the casing with its lid in the closed position;

FIG. 6 is a right side elevational view of the casing with its lid in the closed position;

FIG. 7 is front elevational view of the casing with its lid in the closed position; and,

FIG. 8 is a rear elevational view of the casing with its lid in the closed position.

The broken lines are for illustrative purposes only and form no part of the claimed design.
